CLAIM

The ornamental design for a wall mounted light fixture having struts, as shown and described.

DESCRIPTION

FIG. 1 is a top perspective view of the wall mounted light fixture having struts showing the new design;

FIG. 2 is a top view of the lighting fixture of FIG. 1;

FIG. 3 is a front view of the lighting fixture of FIG. 1;

FIG. 4 is a right side view of the lighting fixture of FIG. 1 where the left side view is a mirror image thereof;

FIG. 5 is a rear view of the lighting fixture of FIG. 1;

FIG. 6 is a bottom perspective view of the lighting fixture of FIG. 1; and,

FIG. 7 is a bottom view of the lighting fixture of FIG. 1.
